Des. 232,021
Patented July 9, 1974

232,021

COMBINED HOUSEBOAT AND TRAILER

Paul F. Stahlheber, 3500 Miami Ave.,
St. Louis, Mo. 63118

Filed May 24, 1972, Ser. No. 256,625

Term of patent 14 years

Int. Cl. D12—10

U.S. Cl. D12—102

FIG. 1

FIG. 2

FIG. 3

FIG. 4

FIG. 5

FIG. 6

FIG. 1 is a perspective view of a combined houseboat and trailer showing my new design;

FIG. 2 is a top plan view thereof;

FIG. 3 is a left side elevational view, the right side being substantially a mirror image thereof;

FIG. 4 is a front elevational view thereof;

FIG. 5 is a rear elevational view thereof; and

FIG. 6 is a bottom plan view thereof;

I claim:

The ornamental design for a combined houseboat and trailer, as shown.
